UNITED STATES PATENT OFFICE.

WILLIAM ERASTUS WILLIAMS, OF CHICAGO, ILLINOIS.

PRESSED-STEEL JOURNAL-BOX.

1,230,057.

Specification of Letters Patent. Patented June 12, 1917.

Application filed July 13, 1915. Serial No. 39,549.

To all whom it may concern:

Be it known that I, WILLIAM ERASTUS WILLIAMS, a citizen of the United States, and a resident of Chicago, in the county of

5 Cook and the State of Illinois, have invented a new and useful Improvement in Pressed-Steel Journal-Boxes, as is set forth in the annexed specification.

My invention relates to journal boxes for 10 railway cars and has for its object the manufacture of journal boxes out of rolled sections of steel and rolled plate whereby a very light, yet very efficient and strong journal box is made.

15 The invention is set forth in the claims.

In my journal box and the method of making it, I provide first a straight rolled bar for the top of the box made of a peculiar section required for the design of the box. I 20 then shear, punch, press and form this section to make the top of the box. I then make what is known as the cellar of the journal box or oil holding casing out of a flat sheet pressed up to form and then apply 25 additional necessary pieces to make the dust guard and the lug for the lid. When the parts are suitably formed, they are assembled and welded, riveted or otherwise suitably connected to form the complete box.

30 Reference will be had to the accompanying drawings, in which:

Figure 1 is an end view of the rolled section out of which the top of the box is formed.

35 Fig. 2 is a plan of the section of the bar shown in Fig. 1 after the same has been sheared and pressed.

Fig. 3 is a section on line 3—3 of Fig. 2.

Fig. 4 is a front view of the structure of 40 Fig. 5.

Fig. 5 is an end view of the structure of Fig. 2.

Fig. 6 is a front elevation showing the plate which is shown in Figs. 2, 3, 4, and 5 45 after the ends have been bent downward to vertical position forming the complete top of the box.

Fig. 7 is a sectional elevation on line 7—7 of Fig. 6.

50 Fig. 8 is a rear elevation of the devices of Fig. 6.

Fig. 9 is a central sectional elevation on line 9—9 of Fig. 7.

55 Fig. 10 is an end view of a rolled bar of a modified form from that shown in Fig. 1.

Fig. 11 is a section on the line 11—11 of Fig. 10.

Fig. 12 is a side elevation of the complete journal box but without the lid.

Fig. 13 is a plan view of the parts shown 60 in Fig. 12.

Fig. 14 is a front elevation corresponding to Figs. 12, 13, but on a slightly smaller scale.

Fig. 15 is a plan detail of one of the rear 65 corners of the top of the box.

Fig. 16 is a section on line 16—16 of Fig. 12.

Fig. 17 is a section on line 17—17 Fig. 12.

Fig. 18 is a section on line 18—18 of 70 Fig. 12.

Fig. 19 is a plan of the cellar detached from the top.

Fig. 20 is a side elevation of the structure 75 shown in Fig. 19.

Fig. 21 is a rear elevation of the dust guard inner wall or flange in a detached position.

Fig. 22 is an elevation of the back piece that forms part of the back end of the box 80 or rear dust guard wall.

Fig. 23 is an end view of the member shown in Fig. 22.

Metal that may be rolled from large ingots is cheaper than cast metal as is shown by 85 the cost of rolled sections compared with steel castings or malleable iron castings, the materials out of which journal boxes are now generally being made. My invention is especially adapted for the use of rolled material.

In railway journal boxes the top of the box sustains the entire load which is put upon a journal and hence the strength is required in this section only. The cellar or 95 lower section of the journal box is simply an oil reservoir in normal service, taking but little or no shock or strain incident to the loads which are put upon the axle.

The top of the journal box must be designed to hold in position what is known as the wedge in railway practice, which wedge is simply a peculiarly formed block of metal inserted between the brass or bearing which lies on the axle, and the top of the journal box. The wedges and the brasses or journal bearings, are made to interlock with one another as to strains endwise and sidewise and the top of the journal box is provided with stops and shoulders 100 105 110

adapted to hold the wedge and bearing in a definite position.

Generally speaking there are three contact points in the top of a journal box, the first and most important is the flat bearing surface upon which the weight of the load rests and then there are what are known as the back stops and the front stops which take up the end thrust of the journal bearing. 10 These three surfaces must be relatively fixed and be of suitable form to meet the service requirements and the rest of the box need not be much more than an inclosure.

In the manufacture of my box, I first provide a rolled section 1 as shown by the end view in Fig. 1, which is provided with two flanges 2 on the top and one flange 3 on the bottom, with a thick portion 4 in the center a relatively thin section 5 for one edge and a 20 thin section 6 for the other edge.

This rolled section comes in long bars and the first operation is to cut it off to the right length as indicated by a plan view in Fig. 2. This is simply a shearing operation.

25 The next operation is to shear out the flange 3 at each end and in the middle portion of the sheet, leaving two small lugs 7 which form the front stops when the piece is finally formed.

30 The next operation is simply the cutting of two slots 80 in the rear end 5.

The next operation is a pressing and bending operation and is usually done hot and it consists in bending the flat section as indicated by 1 to the form shown in plan view 2 and end view 5. In this operation there are pushed down the two projections 8 at the ends of the plate and a lip or flange 9 is turned up at the back of the plate and a 40 curved lip 10 is formed at the front of the plate.

The next operation consists in bending the ends of the plate down to the form shown in Figs. 6, 7, 8 and 9. The projections 8 are then in vertical positions and form the shoulders for the back stops. The front stops 7 are so positioned on the plate that when the bending of the ends takes place to vertical position, the projections 7 abut into 50 the angle of the bend, making a closure of the projections or front stops 7 with the vertical walls of the top piece after the latter is bent.

Instead of swaging or drawing the metal 55 down to form the projections 8, I may roll two additional flanges 11, Figs. 10 and 11 and cut them away as indicated by 12 in Fig. 11, leaving the central portion of the plate smooth in the region where it comes in 60 contact with the wedge on the inside of the box.

Instead of shearing out the flange 3 and the flanges 11 as last described to form the stops, I may when the metal is heated in the 65 pressing operation above mentioned, push

down these flanges to approximately the flat surface of the plate at the points where they are not needed, and thus save the shearing away of the flanges as described.

After the hot operations of swaging and bending have been performed as above indicated, the whole top is then submitted to a cold pressing operation which forms it to exact size. In this operation or at another operation, there are punched four holes 13 and two holes 14 through the top body of the top pieces (see Figs. 13, 15, 16 and 17). In this operation there is also performed a shearing operation which trims out to size the notches 15 (see Fig. 15). The purpose 80 of the holes and the notches is to permit the entrance of projections 23, 24, 25 and 29 from the cellar which registers with the holes.

The cellar is indicated by 16 and may be 85 made in any suitable form desired, as relates to its general outline, and is here shown as being provided with a stiffening boss or projection 17 on the bottom of the cellar which may serve for a seat for a jack screw 90 head for jacking up the car truck. The back end of the cellar is formed with a stiffening rib 18 which also forms a recess in which to hold a flange 19 which forms the interior wall of the dust guard pocket indicated 95 by 20.

The top portions of the sides of the cellar are off set as indicated by 21, Fig. 18 so as to enter on the inside of the vertical walls of the top piece and yet have the side walls of 100 the cellar just below the top piece the full width of the side wall of the top piece. Into the top of the side walls of the cellar there are embossed the two projections 22 which fit over the projections 8 of the top piece and 105 thus form what are called the back stops of the journal box. Projections 23 and 24 of the sides of the cellar extend up through the holes 13 and are bent over as is indicated by Figs. 12, 13 and 16, and thus securely lock 110 the two sections of the journal box together.

Accurate registry of the middle portions of the cellar and top is secured by means of projections 25 formed on the cellar walls and entering corresponding holes 14 in the 115 top member.

Lips or flanges 26 are turned over on the remaining edges of the top sides of the cellar extending inward and forming as it were, stiffening flanges for the top edges of 120 the cellar portion of the box and these flanges rest against the top of the inside of the journal box as is indicated by Figs. 16 and 17.

At the rear of the box the top portions of 125 the back end or back flanges of the cellar are bent outward or offset as is shown by 27 Figs. 12, 19 and 20 and a U-shaped connecting piece 28 embraces the offset portions 27 and forms a closure across the top at 130

the back wall of the dust guard space or cavity 20.

At the rear of the cellar member and at the top of the projections 18 are projections 29 having shoulders 30 which fit against shoulders 31 of the flange 9 as shown in Figs. 13, 15, and these last mentioned projections fit snugly in the spaces 15, whereby the cellar and top members are interlocked.

10 The flange 19 is provided with flanges 32 to fit the inside of the rib 18 but these flanges do not extend across the bottom of the cellar but stop part way up the sides as is indicated by the dotted lines 33, Fig. 12.

15 The main body of flange 19 is cut away at 34 at the ends just underneath the top surface of the top piece, and thus forming a shoulder that projects under the back flange 9 of the top piece and holds the flange 19 down into position into the rib 18 of the box. Thus the inside wall of the dust guard cavity 20 is automatically locked in place when the cellar and top are joined together.

125 The top, cellar, the flange 19 and the piece 28 are further fastened together by spot welds 35 as is indicated by Fig. 12.

To the front end of the box I secure a lug 36 of any suitable form or construction 30 which furnishes the pin hole for the journal box lid. This lug 36 may be spot welded, riveted or otherwise suitably secured to the top piece of the box.

My journal box as is here shown is designed to be used particularly with what is known as a side frame truck, wherein a steel casting or other suitable form of truck frame fits into the guide way across the top and down the sides of the journal box between the flanges 2 of the top piece 40 of the box. The guide ways of the side frame or truck member which rides on the journal box, normally extend below the bottom of the sides of the top piece and by

145 making my cellar project out as I do, to the full width of the top piece below the top piece, the truck member then engages the sides of the cellar below the top piece so that in case of derailment or any unusual 50 strain on the sides of the cellar, such strain is taken up also by the truck frame and the cellar is not required to sustain on its own account severe shocks and this permits a lighter construction of cellar than might 55 otherwise be required.

The flanges 2 securely stiffen the whole box against strains which might produce diamond-shaped distortions and the projections 8 also serve in this stiffening feature.

60 It is essential to have a smooth flat surface on the top and inside of the box as is indicated by 38, Fig. 7 where the wedge comes in contact and hence I roll the bar 1 with a smooth flat surface on the inside. However, 65 when the journal box is finished it is de-

sirable to have some considerable clearance on the inside of the box on each side of the back stops or projections 8 and 22, hence in bending over the sides of the top plate as indicated by Figs. 2, 5, 6, 7, 8 and 9 I bend 70 the thin sections on each side of the flanges 2 out to the alignment of the thicker portion 5, thus there occurs the reentrant curves 39, Fig. 13. While the bottom of the plate 1, Fig. 1 is substantially a smooth line all 75 save the flange 3, the same surface where it appears as the side walls of the finished top has an irregular line as indicated by the dotted lines 40, Fig. 13. This has the effect of stiffening the corners of the top piece 80 and is a desideratum.

The loads which are borne by the axle and hence transmitted through the box, are directly applied on the thick portion 4 of the top piece, and since this is integrally 85 united with the front and back stops as indicated, we have a very secure box notwithstanding that the rest of the top and the cellar may be made out of comparatively thin material.

90 My cellar extends as a continuous sheet entirely down the sides and across the bottom making no joints below the top of the inside, whereby leakage of oil at joints or rivets is prevented. The custom of the men 95 who oil car journals is to pack waste securely in around on all sides that are open below the brass, and thus if there are any joints in a cellar below the top of the journal box the oil is likely to leak out at the 100 joints or at the rivet holes.

What I claim is:

1. A journal box made of top and cellar portions adapted to be joined together in vertical lines, the edges of one overlapping 105 the edges of the other and interlocked as to end thrust, said top having suitable holes and the cellar having corresponding projections secured in said holes.

2. A journal box composed of top and 110 cellar sections, the top section overlapping the top edges of the cellar and the cellar sheet extending up the entire vertical sides of the box on the inside of the top section and formed with shoulders that act as the 115 back stops and said top sections being provided with projections which engage said back stops.

3. A journal box formed of top and cellar sections, the top section provided with guide 120 ribs on the outside and front stops and thrust projections on the inside, the cellar section telescoping the inside of the top section in a vertical line and provided with shoulders for forming the back stop, said 125 shoulders adapted to be supported against thrust by the supporting projections of the top section.

4. A journal box made of top and cellar sections adapted to be overlapped and inter- 130

locked in a vertical line, the cellar section passing up on the inside of the side walls of the top section, said cellar flush with the sides of the top section and offset to pass 5 inside the top section where the parts meet.

5. A journal box composed of a top section and a cellar section, the top section made of a rolled bar with guide flanges thereon and bent transversely of the flanges 10 to form vertical sides extending part way down the box, a cellar made of a sheet of metal and drawn up to form and telescoped on the inside of the top section.

6. A journal box composed of a top section and cellar section, the top section composed of a bar having longitudinal guide and stop flanges rolled thereon and the flanged portion of the section being bent transversely of the flanges to form a one-piece top extending part way down the sides of the box and provided with ribs continuing across the bending lines, and a cellar section formed of a sheet and overlapping the side portions of the top section.

25 7. A journal box composed of a top section and cellar section the top section composed of a rolled bar having guide and stop flanges thereon and bent transversely of the flanges forming sides extending part way 30 down the sides of the box, a cellar section formed of a sheet and overlapping the side portions of the top section on the inside thereof.

35 8. A journal box composed of a top and a cellar section, the top section made of a rolled bar with guide and stop flanges and thick middle and thin edge portions, said bar bent transversely of the flanges to form side members extending part way down the 40 sides of the box, the cellar section telescoping the inside of the top section and formed to fit the inside contour of the top section.

45 9. A journal box made of top and cellar portions, the top section a rolled bar having a relatively thick central continuous longitudinal body with thin lateral extensions,

the bar bent transversely of the direction in which it was rolled and across said body to form vertical side members, the thin edges being bent up to form front and rear flanges 50 on both ends, and the cellar being formed of a sheet and adapted to telescope and overlap the side members of the top sheet.

10. The combination with a metal sheet drawn up to form a journal box cellar section having rear inwardly turned lateral flanges, of a back piece serving as the upper part of a dust guard and connecting said flanges.

11. The combination with a metal sheet 60 drawn up to form a journal box cellar section having at its rear end inwardly turned lateral flanges, of a back piece U-shaped in cross section, extending across the rear end of the cellar, embracing and connecting the 65 upper portions of said flanges and serving as the upper member of a dust guard.

12. A journal box composed of top member and cellar member, the top member having notches at its rear end and side projections that extend over the upper side portions of the cellar member, and the cellar member having projections to enter said notches and secure a registration of the parts 70 against central displacement.

13. A journal box composed of top member and cellar member, the top member having side projections that extend over the upper side portions of the cellar member, projections on the rear of the cellar member 80 that enter notches on the rear of the top member and secure a registration of the parts against central displacement, and a back piece extending across the back flanges of the cellar and secured thereto.

85 Signed in Chicago, in the State of Illinois, and county of Cook this 9th day of July, 1915.

WILLIAM ERASTUS WILLIAMS.
